UNITED STATES PATENT OFFICE.

JOHN A. BRODIN, OF CHICAGO, ILLINOIS.

MOLDING APPARATUS.

SPECIFICATION forming part of Letters Patent No. 791,177, dated May 30, 1905.

Application filed February 8, 1904. Serial No. 192,637.

To all whom it may concern:

Be it known that I, JOHN A. BRODIN, a citizen of the United States, residing at Chicago, in the county of Cook and State of Illinois, have invented a certain new and useful Improvement in Molding Apparatus, of which the following is a specification.

My invention relates to machines or devices for making molds for castings.

10 My invention is illustrated in the accompanying drawings, wherein—

Figure 1 is a plan view of a molding-machine with the pattern in place. Fig. 2 is an inverted plan view of the pattern-carrier and pattern. Fig. 3 is a vertical section on line 3 3 of Fig. 1. Fig. 4 is a vertical section on the same line with the parts in another position, showing the pattern ready to be lowered after the mold has been made. Fig. 5 is a detail side elevation to show the latch for locking the patterns into position. Fig. 6 is a vertical section similar to Fig. 3 of a modified form of the machine. Fig. 7 is a side view, partly sectional, of an interlocking brake-shoe, the dotted line xx showing the line of parting of the drag and cope.

Like parts are indicated by the same letters in all the figures.

Referring to Figs. 1 to 5, inclusive, A is the frame of the machine supporting the stripping-plate B, which carries the flask C, secured to it on one side by the pin B', integral with and extending upward from the projecting lug B² on the stripping-plate B and passing through a perforation in the rim C' of the flask, and on the other side by the pin C², integral with and extending downward from the rim C' and passing through a like perforation in the lug B³ on the stripping-plate B. D is a rectangular frame braced underneath by the horizontal arms D', carrying the pattern E and resting upon a vertical support D², which moves freely through an aperture A' in the frame A, so as to allow the pattern E to be raised and lowered through apertures B⁴ in the stripping-plate B. The pattern E is secured to the carrier D by bolts D³ or in any preferred manner and has two movable hook-shaped parts E', turned in opposite directions and projecting through the apertures E² in the pattern

E, so as to give the desired contour to the mold at these places, the apertures E² being so conformed as to contact closely with the projecting parts E' when such parts are at their farthest extension therethrough. The 55 projecting parts E' are integral with two like arms E³ E⁴, which are pivoted between pairs of downwardly-extending lugs E⁵ of the pattern E and have convexed faces E⁶, which rest upon the horizontal faces of angle-irons D⁴ on 60 the sides of the carrier D when the projecting parts E' are at their farthest extension through the apertures E². At a point upon the arm E³ below its connection with the pattern E is pivoted by the pin E⁷ one end of the bent bar F, 65 the other end being slotted, so as to make an adjustable connection by means of bolts F' and nuts F² with the slotted end of the bar F³, which at its other end is pivotally connected to one end of the lever-arm F⁴. The other extremity of 70 lever F⁴ is pivotally connected to an upwardly-curved arm F⁵, similarly joined to the other arm, E⁴, of the two like arms by the pin E⁸ at a point below its connection with the pattern E. The lever-arm F has a hub F⁶ at its middle 75 embracing the shaft G, to which it is rigidly secured by the screw F⁷. The shaft G turns in bearings in the supporting-arms G', which are secured to and project horizontally from 80 one end of the carrier D and are provided with lugs G², having threaded perforations for the reception of the set-screws G³, one of which is headed upward, as shown in Fig. 5, the other in the opposite direction. In alignment with the set-screws G³ on the shaft G are the 85 hubs G⁴, fastened to the shaft G by the screws G⁵ and carrying oppositely-pointing stop-lugs G⁶, which contact with the ends of the set-screws G³, so as to limit the turn of the shaft G in each direction. One end of the shaft G 90 terminates on the crank G⁷ and handle G⁸. Upon the crank G⁷ rests the grooved end of the latch G⁹, pivoted at G¹⁰ on the stripping-plate B and having the stop-lugs G¹¹, which engage with the pin G¹² to keep the latch G⁹ 95 from turning too far either way. This form of my machine as illustrated is particularly adapted for making the upper portion of molds for casting interlocking brake-shoes, as indicated by I, Fig. 7, and particularly the 100

aperture in the mold for forming the projecting part I'.

Fig. 6 is a vertical section, similar to Fig. 3, of a modified form of my machine, wherein the projecting portions E' of the pattern E extend approximately horizontally through the apertures E² in the upright faces of the pattern, necessitating a form of mechanism somewhat different, though without departure 10 from the scheme of my invention as above described. The parts E' are in this form made to slide through slots E⁹ in vertical supporting parts E¹⁰ of the pattern E and are integral with like downwardly-extending arms E³ 15 E⁴, which are joined to the opposite ends of the lever-arm F⁴ by like pivotal connections—viz., arm E³ by the adjustable slotted and bolted arms F and F³, as in the form of machine heretofore described, and the arm E⁴ by 20 two similar slotted arms F⁸ and F⁹, rigidly fastened together by the bolts F¹⁰ and nuts F¹¹. I have also provided the latches H. (See Fig. 2.) These latches are particularly required in the form of my machine last 25 described because of the peculiar shape and position of the projecting parts of the pattern, which might be seriously damaged if the pattern were lowered while such projections were extended. I may also, however, use 30 these latches upon the other form of machine for the same purpose. These latches H have perforations H' at one end, through which pass freely the pins H², rigid with the shaft G and extending downward and outward therefrom, the other ends of the latches H sliding 35 through supports H³ on the under side of the carrier D. On the outer sides of the latches H are the lugs H⁴, which are slightly above the inwardly-extending lugs H⁵ on the upper 40 right support A² of the plate B when the pattern-carrier D reaches its highest point. When the crank G⁷ and shaft G are turned to set the projecting parts E in position, the lugs H⁴ will be drawn by the outward revolution of 45 the pins H² so as to engage the lugs H⁵ and the pattern E, held in position on the machine. On this form of machine can be made the lower portions of the molds for casting interlocking brake-shoes, as shown at I², Fig. 50 7, and in particular the apertures in such molds which form the projecting parts I³ of such castings.

The purpose of my invention, it will be seen from the foregoing, is to provide a means for 55 making molds for castings which will obviate the necessity of coring, the means provided involving the use of a pattern having those parts which would, if rigid with the rest of the pattern, prevent the separation of pattern 60 and mold, made capable of being first withdrawn from contact with the mold, so that the free separation of mold and pattern becomes possible.

In operation (referring to Figs. 1 to 5, inclusive) the projecting parts E' are set by

turning the crank-handle G⁸ until the convexed faces E⁶ rest on the angle-irons D⁴, the turn of the shaft G being arrested at this point by one of the stop-lugs G² contacting with its set-screw G³. The latch G⁹, the 70 grooved end of which follows along the crank G⁷, prevents the projecting parts E' from being forced back by impact of the sand in the process of making the mold. When this process is completed, the latch G⁹ is lifted and the 75 crank G⁷ turned in the opposite direction, so as to withdraw the projecting parts E' through the apertures E² enough so that the pattern may be lowered without injury to the mold. The backward turn is arrested at the proper 80 point by the contact of the other stop-lug G² with its set-screw G³. In the modified form of machine the horizontal projections E' are set in manner similar, the latch H operating 85 in the way above described to lock the carrier 80 to the frame and prevent injury to the projecting parts E' by an accidental lowering of the carrier. When the mold is completed, in similar manner the projecting parts E' are 90 retired by being slid backward through apertures E² and slots E⁹ in the supports E¹⁰.

While the devices above described in specification and drawings are particularly designed for making sand molds for interlocking brake-shoes, it will be clear that my invention could be used in other cases where similar conditions are met with. It will also be clear that while I have described in detail the various constructions embodying my invention these constructions may be varied in 95 many particulars and parts omitted and others used with parts not herein shown without departing from the spirit of my invention. I therefore do not limit myself to the devices 100 illustrated.

I have used the word "arm" to refer to the connection between the projecting part or pattern projection and the rock-shaft or driving device; but I also use the word "link" 105 for the same purpose, since it in ordinary construction involves a link-like motion as distinguished from a rotary motion in the operation of the devices. The driving mechanism or rock-shaft is preferably mounted on or in some way associated with or placed so as to 110 operate in connection with the pattern.

I claim—

1. In a molding-machine the combination of a supporting-frame, a flask, a movable pattern-carrier, a pattern thereupon having apertures therein, projecting parts adapted to extend through the pattern, a rotating device 120 associated with the pattern-carrier, adjustable arms connecting the projecting parts with the rotating device so that when such device is 125 rotated, the projecting parts will be simultaneously moved in and out of such apertures, and means for operating such rotating device.

2. In a molding-machine the combination of a supporting-frame, a flask, a movable pat- 130

- tern having parts thereof capable of motion independent of the rest of the pattern, means for simultaneously moving such parts comprising a rotating device having connections 5 at different points with each of such parts, a slot in the supporting-frame, and a latch associated with such rotating device and adapted to be drawn into and out of such slot when the rotating device is operating.
- 10 3. In a molding-machine the combination of a supporting-frame, a flask, a movable pattern adapted to be reciprocated in and out of the flask having an aperture therein, a projecting part movably connected with the pattern 15 and adapted to extend through such aperture, a rotating device associated with the pattern, an arm connecting the projecting part with the rotating device so that when such device is rotated, the projecting part will be moved 20 in and out of such aperture, means for operating such rotating device, and means for adjustably limiting the amount of rotation of such device in each direction.
4. In a molding-machine, the combination 25 of a supporting-frame, a flask, a movable pattern-carrier, a pattern thereupon having an aperture, a projecting part adapted to extend through the aperture, a rotating device associated with the pattern-carrier, an adjustable 30 arm connecting the projecting part with the rotating device so that when such device is rotated, the projecting part will be moved in and out of such aperture, and means for operating such rotating device.
- 35 5. In a molding-machine, the combination of a flask, a pattern adapted to be reciprocated in and out of the flask, a projection on such pattern movably connected therewith and extending therethrough, and means for withdrawing 40 such projection from its aperture in the mold, such means comprising a rock-shaft with a rotating arm thereon and a pivoted link connecting such arm with the projecting part.
- 45 6. In a molding-machine, the combination of a flask with a movable pattern adapted to
- be received by the flask, pattern projections extending through apertures in the face of the pattern and in different directions into the flask, and movably mounted on the pattern, a 50 driving part, and connections each containing a separate link from such driving part to such pattern projections whereby when the driving part is operated the movable projections are retracted within the pattern. 55
7. In a molding-machine, the combination of a flask, a movable pattern adapted to be received by the flask, a projecting part mounted on the pattern and extending through an aperture in the face thereof into the flask, a driving device associated with the pattern, an adjustable connecting device containing a link from the driving device to the projecting part so that when such driving part is operated the 60 projecting part will be retracted. 65
8. In a molding-machine, the combination of a flask with a movable pattern adapted to be received by the flask, pattern projections extending through apertures in the face of the pattern and in the desired directions into the 70 flask, and movably mounted on the pattern, a driving part, connections from such driving part to such pattern projections, and an adjusting device in one of such connections whereby when the driving part is operated the 75 movable projections are retracted within the pattern, and by operating the adjustment the pattern projections may be made effectively equal.
9. In a molding-machine, the combination 80 of a flask, a movable pattern, apertures in such pattern, projecting pattern parts extending through such apertures in contrary directions, and means for simultaneously withdrawing such projecting pattern parts, comprising a 85 driving part and a connection, including a link from such driving part to each of such projecting pattern parts.
